METHOD FOR TESTING AND PRODUCING
THE FLUIDS OF THE EARTH FORMATIONS
ENCOUNTERED IN WELLS

Elwin B. Hall and Arthur L. Armentrout, Los Angeles, Calif., assignors, by direct and mesne assignments, to Security Engineering Co. Inc., a corporation of California

Application March 10, 1939, Serial No. 260,952

5 Claims. (Cl. 166—21)

This invention has to do with the testing and producing of wells and has particular reference to a method for testing and producing the fluids of the earth formations encountered in wells. A general object of this invention is to provide a rapid, efficient and practical method for determining the productivity of the earth formations encountered in wells and for recovering or producing such fluids.

This application is a continuation in part of our co-pending application Serial No. 80,696, filed May 20, 1936.

Another object of this invention is to provide a simple, safe and commercially practical method for determining the productivity of the earth formations in a well and for producing or recovering the fluids from such formations, which method does not endanger the well and cannot necessitate expensive time consuming fishing operations. In the producing and testing of wells such as oil wells and gas wells it has been the common practice to install steel liners and casings and to utilize steel testing equipment. The steel liners and casings are usually run into the well to extend into or through the producing strata and the testing equipment is usually arranged to extend into the open portion of the well bore. In many instances the steel liners, casings and/or testing equipment become lodged, caught or immovably fixed in the well. The steel equipment thus caught in the well cannot be drilled up by the well drilling equipment and attempts must be made to withdraw it or fish it from the well with fishing tools. These fishing operations are very expensive and time consuming and in many cases fail or result in the recovery of even a portion of the lost equipment. Where the lost or caught equipment cannot be recovered by fishing operations it is necessary to attempt to sidetrack the well past the caught equipment and if this fails the well must be abandoned.

Another object of this invention is to provide a method for determining the productivity of the earth formation in a well and for producing a well, that is to be deepened or that may be deepened at a later date, which leaves the well bore free and entirely unobstructed at the completion of the testing or producing operations.

Another object of this invention is to provide a method for testing the productivity of a well that utilizes equipment in the well suitable for a test of short duration or for an extended test, which equipment may be left in the well following a favorable production test to be utilized in the

producing of the well, and that may be easily, quickly and inexpensively removed from the well at any time without resorting to expensive, uncertain fishing operations.

Another object of this invention is to provide a method for accurately testing the productivity of the earth formation in a well and for producing the fluids from the earth formation that is characterized by the employment of well equipment that may be broken down and eliminated from the well by a suitable concentrated acid or other solvent agent, to leave the well bore free and unobstructed for subsequent operations.

Another object of this invention is to provide a method for testing the productivity of the earth formations encountered in a well and for producing the fluids from such formations that requires a minimum number of simple rapid operations that do not in any way endanger the well.

Another object of this invention is to provide a method of the character mentioned that employs a well casing or liner and associated equipment that are substantially unaffected by the fluids that may be present in the well and, therefore, may be left in the well indefinitely and yet are such that they may be eliminated or removed from the well at any time by breaking them down or dissolving them with material introduced into the well.

The various objects and features of our invention will be fully understood from the following detailed description of typical preferred manners of carrying out the method of the invention, throughout which description reference is made to the accompanying drawing, in which:

Fig. 1 is a vertical detailed sectional view of the lower portion of a typical well illustrating apparatus in position in the well for testing or producing the fluids from the earth formation. Fig. 2 is a view similar to Fig. 1 showing the condition of the well following the removal of the testing or producing equipment in accordance with the method of the invention, and Fig. 3 is a vertical detailed sectional view of the lower portion of a well showing another form of casing or liner arranged in position to produce the well in accordance with the method of the invention.

The method of the present invention may be carried out with apparatus or equipment varying somewhat in character and the method is capable of variation to suit it for employment under the different conditions that may exist in the well. We will proceed with a description of the well testing and producing equipment illustrated in

Fig. 1 of the drawing and will then describe one manner of performing the method of the invention employing such equipment.

The well testing and producing equipment illustrated in Fig. 1 includes a tubular liner body 10 capable of being broken down in the well, an adapter 11 at the upper end of the liner body 10, a tubular well string S detachably connected with the adapter 11 and a packer 12 on the adapter 11 for packing off the fluid in the well casing C from the earth formation being tested or produced.

The body 10 is an elongate tubular member or assembly adapted to be arranged in the well to receive the fluids from the earth formation for the purpose of testing the productivity of the 15 earth formation or for recovering or producing the fluids from the earth formation, or both. As illustrated in Fig. 1 of the drawing, the body 10 is adapted to extend into or through the open portion A of the well bore B below the lower end of the set well casing C. The well casing C is set and cemented in the usual manner having its lower portion and its shoe 13 embedded in a body of cement 14 resting upon a shoulder 15 on the wall of the well bore B. The well bore B, as illustrated, has been deepened or extended below the shoulder 15 to have an open portion A extending through the stratum or strata D of earth formation to be tested or produced. The length of the body 10 depends upon the depth or extent 30 of the open portion A of the well bore B and the body 10 may be formed of a single section or of a multiplicity of coupled or connected sections as conditions may require. In the case illustrated in the drawing the body 10 comprises several 35 tubular sections 10^a coupled by threaded couplings 16.

The liner body 10 is proportioned to extend into the open portion A of the well bore with suitable clearance and is adapted to be supported in any selected manner. In the arrangement illustrated the lower end of the liner body 10 rests on the bottom of the well bore B to be supported by this engagement. The liner body 10 illustrated in the drawing is provided with a multiplicity of spaced slots 18 to admit the fluids from the earth formation or strata D to it so that said fluids may pass upwardly through the body 10 and adapter 11 to the string S.

The character of the material of which the liner body 10 is formed is an important feature of the invention. In accordance with the invention the body 10 is formed of a material that is soluble under conditions that the operator may establish in the well but that is resistant to and substantially unaffected by the fluids that may be normally present in the well. The body 10 is formed of aluminum or an aluminum alloy. It is to be understood that where reference is made to the body 10 as formed of aluminum or an aluminum alloy the body 10 is meant to include its one or more sections 10^a and its one or more couplings 16. The aluminum or aluminum alloy of which the body 10 is formed has a number of inherent physical properties or characteristics 50 that render the body 10 practical, dependable and particularly adapted for its intended use. The body 10 being formed of aluminum or a suitable aluminum alloy has a substantial tensile strength so that there is little or no danger of the body failing because of its own weight even though it may be of great length. The aluminum and the aluminum alloys of which the body 10 may be formed have a low specific gravity. Accordingly, the body 10 formed of a material hav-

ing a substantial tensile strength and a low specific gravity may be fabricated in substantially any desired length without danger of parting or failing through its own weight. The substantial tensile strength of the aluminum or aluminum alloy of which the body 10 is constructed renders the threads and like parts of the body structure, 5 strong and durable. Furthermore, the aluminum or aluminum alloy of which the body 10 is constructed is ductile and readily machined so that the body 10, the couplings 16, etc. may be provided with good regular threads and connecting parts.

Wells often contain saline fluids and weak caustic fluids that may attack substantially pure aluminum. Accordingly, in some instances it may be preferred to construct the body 10 of an aluminum alloy that is non-corrosive and resistant to the action of the fluids encountered in wells. Silica or chromium, or both, may be alloyed with the aluminum of which the body 10 is to be constructed to produce an alloy that is resistant to the fluids encountered in deep wells. It is to be understood that the alloy of which the body 10 is formed is soluble under conditions that the operator may establish in the well. Alloys of aluminum such as we have referred to are readily broken down by the materials or solvents to be later described.

The adapter 11 is provided to connect the liner body 10 with the lower end of the string S and to support the packer 12. The particular adapter 11 illustrated includes two relatively shiftable sections 20 and 21. The section 20 is detachably secured to the lower end of the string S having a threaded socket 23 in its upper end receiving the threaded lower part of the string S. The threads of the string S and the socket 23 are lefthand threads whereby the string may be easily unthreaded from the adapter 11 without endangering the other threaded connections of the string. The lower section 21 of the adapter 11 is threaded to the upper end of the body 10. A longitudinal opening 25 extends through the section 21 to place the interior of the liner body 10 in communication with the opening 22 and the string S. The upper end portion of the section 21 is shiftable in the opening 22 of the section 20 and a shiftable connection is provided between the two sections 20 and 21. This connection may comprise pins 27 on the section 21 shiftable in grooves 26 in the section 20. A downwardly and outwardly inclined or tapered surface 28 is provided on the exterior of the adapter section 21 to cooperate with the packer 12.

In accordance with the invention the adapter sections 20 and 21 are formed of aluminum or an aluminum alloy of the character referred to above, whereby the adapter 11 may be broken down or dissolved in the well in the same manner as the body 10.

The packer 12 may comprise an annular body of rubber, or the like, arranged around the adapter section 21. The packer 12 has a tapered internal surface 30 cooperable with the surface 28 and the upper end of the packer is engageable by the lower end of the adapter section 20. The periphery of the packer 12 is adapted to normally have suitable clearance with the interior of the casing C so that the equipment may be readily run through the casing.

The string S is provided to run or lower the equipment into the well and to receive and conduct away the fluids obtained from the tested or producing strata D. The string S may be a typi-

cal tubular well string constructed of steel drill pipe or tubing.

The method of the present invention may employ the apparatus illustrated in Fig. 1 of the drawing to determine the productivity of the earth formation penetrated by the lower portion A of the well bore or to produce or recover the fluids from the said earth formation. In carrying out the method of the invention with the apparatus illustrated in Fig. 1 the body 10 is fabricated to be of correct length, that is, to extend through the lower portion A of the well bore. The adapter 11 provided with the packer 12 is secured to the upper end of the body 10 and the adapter in turn is connected with the lower end of the string S. The equipment is then run into the well on the lower end of the string S to a position where the lower end of the body 10 rests on the bottom of the well bore.

Following the positioning of the equipment as just described, the weight or a portion of the weight of the string S is imposed on the packer 12 through the medium of the shiftable adapter section 20 to expand the packer. The weight imposed on the packer 12 causes the tapered surfaces 28 and 30 to cooperate in a manner to expand the packer 12 so that it seals with the interior of the well casing C. The packer 12 may be maintained under compression to seal with the interior of the casing C and fully seal off the interior of the casing from the lower portion A of the well bore.

The liquid that may be present in the lower portion A of the well bore may be pumped, bailed, swabbed or otherwise removed so that the fluids produced by the strata D will be uncontaminated. The fluids produced from the strata D will in most cases be under pressure to flow through the perforations 18 into the body 10 and up through the body 10, the adapter 11 and the string S. Under some conditions the strata D may produce fluids in a sufficient quantity and under sufficient pressure to flow upwardly through the string S to the ground surface. In other instances it may be found necessary to withdraw the fluid produced into the string S by bailing or pumping operations. If the equipment or apparatus is being employed to test the productivity of the earth formation the quantity of fluid produced from the strata D may be readily determined to accurately ascertain the productivity of the formation. If the equipment is being utilized to produce the well the fluid produced from the strata D may be allowed to flow out through the string S or may be pumped from the string S in any of the well known manners.

Where the equipment is installed for the purpose of producing the well and it is found that the strata D does not produce in paying quantities it may be found desirable to deepen the well. In other cases it may be preferred to allow the well to produce through the string S or to pump the produced fluid through the string S and when the production is appreciably lessened the well may be deepened. In either event the equipment may be easily and quickly removed from the well to leave it unobstructed for drilling and other operations. Where the equipment is installed as described above, for the purpose of testing the productivity of the earth formation the equipment may be removed from the well in the manner to be described, immediately following the test, or it may be left in the well to produce the fluid from the strata D if it is found that the strata D is producing in paying quantities.

In accordance with the present invention the equipment comprising the body 10 and the adapter 11 may be removed or eliminated from the well when desired or necessary by decomposing, destroying, dissolving or breaking down the equipment in the well by the action of a solvent. In most cases it may be found desirable to disconnect the string S from the adapter section 20 and to withdraw the string S from the well before breaking down the equipment with the solvent. It is to be understood that the body 10, the adapter 11 and the packer 12 may be removed from the well on the string S where such an operation is possible or desirable. However, where there is any difficulty encountered in removing the equipment from the well on the string S because of caving of the well or sanding up of the well or any other reason, the string S may be easily disconnected from the adapter 11 and withdrawn from the well to leave the testing and/or producing equipment in the well to be decomposed or broken down by the solvent.

A strong or concentrated solution of hydrochloric acid, or any other solvent that is capable of breaking down or dissolving aluminum and its alloys mentioned above, is introduced into the well to come into contact with the body 10 and the adapter 11. Hydrochloric acid is effective as the solvent for breaking down the aluminum parts in the well. Hydrochloric acid is inexpensive, is usually readily available and reacts with aluminum to produce aluminum chloride which is readily soluble in water and can be easily flushed from the well. A strong or concentrated solution of hydrochloric acid may be introduced into the well to dissolve the body 10 and other aluminum parts. The reaction of the hydrochloric acid with the aluminum parts in the well in the production of the water soluble aluminum chloride may be represented as follows:

Where hydrochloric acid is employed to remove or break down the body 10 and the adapter 11 it may be found desirable or necessary to add an inhibitor to the hydrochloric acid solution to prevent the solvent from attacking the steel parts in the well. The inhibitor used may be ortho-ditolythiourea known as "Rodine" and represented by the formula $2(\text{CH}_3\text{C}_6\text{H}_5)\text{NHCSNH}$; thiocarbamide NH_2CSNH_2 ; dibenzyl aniline disclosed in Patent No. 1,719,650 and represented by the formula $\text{C}_6\text{H}_5\text{N}(\text{CH}_2\text{C}_6\text{H}_5)_2$; dibenzyl amine $2(\text{C}_6\text{H}_5\text{CH}_2)\text{NH}$; or triphenyl guanidine $2(\text{C}_6\text{H}_5\text{NH})\text{CNC}_6\text{H}_5$. While the three last named inhibitors are primarily for use with sulphuric acid H_2SO_4 they may be successfully employed with hydrochloric acid HCl when the latter is used as the solvent in the presence of ferrous equipment. The proportion of the inhibitor used may, of course, be varied as the operating conditions demand. A solution of caustic soda (sodium hydroxide) is also effective in breaking down or dissolving the body 10 and adapter 11 in the well. A suitable quantity of a 20 per cent solution of sodium hydroxide may be introduced into the well to react with or break down the aluminum parts. This reaction may be represented as follows:

First reaction:

Second reaction:

75 A sufficient quantity of the solvent material is

introduced into the well to assure the complete dissolution of the body 10 and the adapter 11. The body 10 and the adapter 11 being formed of aluminum or an aluminum alloy are quickly dissolved, decomposed or broken down by the solution thus introduced into the well. The solvent or material employed to break down the body 10 and the adapter 11 may fully decompose or eliminate the body and the adapter from the well to leave the well clear and free for subsequent operations.

The solvent or material for breaking down or decomposing the body 10 and the adapter 11 may be delivered to the lower portion of the well to come into contact with the body 10 and the adapter 11 in any selected manner. For example, it may be pumped into the well, lowered into the well in a bailer, or lowered into the well in a suitable container. The solvent or decomposing agent may be delivered to the lower portion of the well in such a manner that no appreciable part of the agent or solvent is lost. The packer being formed of rubber or the like may be substantially unaffected by the agent or solvent for breaking down the body 10 and the adapter 11 and may remain in the well, as illustrated in Fig. 2. However, the packer may be easily destroyed, broken up or drilled away by suitable tools, for example, by drilling tools that may be employed to deepen the well. Following the introduction of the acid, solvent, or decomposing agent into the well a suitable period is allowed to elapse to assure the complete breaking down or dissolution of the aluminum body 10 and the aluminum adapter 11. Fig. 2 of the drawing illustrates the condition of the well following the elimination or dissolution of the body 10 and the adapter 11.

Following the breaking down or dissolving of the body 10 and the adapter 11 the solvent or dissolving medium may be removed from the well. The solvent or dissolving agent may be pumped, bailed, or flushed from the well. Subsequent to the removal of the solvent or dissolving agent the well may be reconditioned for further production, may be deepened to penetrate lower productive strata, or any other required or desired operations may be carried on in the well. It is to be observed that the method provides for the rapid, efficient and economical testing of the productivity of the earth formation in the open lower portion of the well or the production of the fluids from the said earth formation, or both, and the subsequent complete elimination of the equipment employed in the well in a safe, rapid and inexpensive manner. The various testing and producing operations may be carried out with the assurance that the equipment installed in the well may be quickly and safely removed or eliminated at any time.

In Fig. 3 of the drawing we have illustrated another manner of carrying out the method of the invention. In the portion of the well bore illustrated in Fig. 3 the casing C has its lower part cemented in the well and the well is extended or drilled beyond the lower end of the casing to have an open lower portion F. The body of cement 14a provided around the lower part of the casing C seals off the upper portion of the well from the open lower portion F. The open portion F of the well may be known to be productive in paying quantities or it may be desired to determine the productivity of the earth formation penetrated by the open portion F of the well. In either event the invention provides

for the installation of a tubular liner body 10b in the open well portion F. The liner body 10b may be supported or suspended in the well in any selected manner. In the particular case illustrated the lower end of the body 10a rests on the bottom of the well and the body is of sufficient length to extend upwardly into the lower portion of the set casing C. The body 10b may be run into the well on the lower end of a tubular well string similar to the string S and following the setting or positioning of the body 10b the string may be detached from the body and withdrawn from the well. In the drawing we have shown the body 10b perforated or provided with a plurality of spaced perforations 18a that may be provided in the body 10b prior to the installation of the body in the well. It is to be understood that the body 10b may be perforated following its installation in the well by any of the well known perforating methods. The elongate tubular body 10b may be sectional and may be fabricated at the ground surface to be of the required length. A lefthand thread may be provided at the upper end part of the body 10b to facilitate its detachable connection with a tubular setting string.

In accordance with the invention the body 10b is formed of aluminum or an aluminum alloy of the character described above. The body 10b is 30 may be formed of an aluminum alloy that is resistant to the fluids encountered in wells so that it may remain in the well for a long period without being appreciably affected by the fluids therein. The body 10b being formed of aluminum or an aluminum alloy is relatively light in weight so that it may be handled by light equipment and the body 10b may be fabricated to be of great length without danger of parting through its own weight. When the body 10b is 40 installed in the well as described above it constitutes a casing or liner in the open well portion F to prevent caving and excessive sanding up of the well.

If the open portion F of the well is to be tested to determine its productivity it may be desirable to first pump, bail out or otherwise remove the mud and other fluids from the casing C and the body 10b. This will allow the fluids from the strata penetrated by the open well portion F to freely flow into the body 10b through its perforations 18a. The fluid thus produced from the earth formation may pass upwardly through the casing C and when necessary may be pumped or bailed from the well. If it is found that the strata penetrated by the open portion F of the well produce in paying quantities the body 10b 50 may be left in the well to act as a production liner. In the event that the production test is unfavorable it may be found desirable to remove or eliminate the body 10b from the well.

The body 10b may be withdrawn from the well by a well string threadedly connected with its upper end or otherwise connected with it. If any difficulty is encountered in withdrawing the body 10b in this manner or if it is not desired to recover the body 10b the invention provides a rapid and effective method for eliminating the body 10b from the well. The body 10b may be dissolved, broken down, or decomposed in the well by a solvent or decomposing agent to leave the well bore entirely free and unobstructed. A suitable concentrated or strong solution of hydrochloric acid, a solution of sodium hydroxide, or any other material capable of breaking down aluminum and its alloys is introduced to the

lower portion of the well to come into contact with the body 10^b. This solvent or agent may be introduced into the well by means of a bailer, a pump or a container lowered into the well and a sufficient quantity of the solvent or agent is employed to assure the complete dissolution of the body 10^b. The body 10^b being constructed of aluminum or an aluminum alloy of the character referred to is quickly broken down or dissolved by the solvent or dissolving agent. Following the breaking down or dissolving of the body 10^b the solvent or dissolving agent may be pumped, bailed, swabbed or flushed from the well. The well is then in condition to be deepened or to be reconditioned for further production.

Having described only typical preferred manners of carrying out the method of our invention, we do not wish to be limited or restricted to the specific details herein set forth, but wish to reserve to ourselves any variations or modifications that may appear to those skilled in the art or fall within the scope of the following claims.

Having described our invention, we claim:

1. The method of operating a well having ferrous metal structures therein and in which it may be advantageous to install a member that subsequently can be readily removed if desired, which method comprises forming said member of an aluminum alloy, positioning said member in the well and removing it when desired by dissolving said member with a strong hydroxide whereby the hydroxide will react and dissolve the aluminum alloy without detrimentally affecting the ferrous metal structures.

2. The method of operating a well having ferrous metal structures therein and in which it may be advantageous to install a member that subsequently can be readily removed if desired, which method comprises forming said member of an aluminum alloy, positioning said member in the well and removing it when desired by dis-

solving said member with sodium hydroxide whereby the sodium hydroxide will react with and dissolve the aluminum alloy under the temperature and pressure conditions normally existing in a well without detrimentally affecting the ferrous metal structures.

3. The method of operating a well having ferrous metal structures therein and in which it may be advantageous to install a member that subsequently can be readily removed if desired, which method comprises forming said member of an aluminum alloy, positioning said member in the well and removing it when desired by dissolving said member with an acid and employing an inhibitor which retards or prevents the acid acting detrimentally upon the ferrous metal structures.

4. The method of operating a well having ferrous metal structures therein and in which it may be advantageous to install a member that subsequently can be readily removed if desired, which method comprises forming said member of an aluminum alloy, positioning said member in the well and removing it when desired by dissolving said member with hydrochloric acid together with an inhibitor which prevents or retards the acid acting detrimentally upon the ferrous metal structures.

5. The method of operating a well having ferrous metal structures therein and in which it may be advantageous to install a member that is apt to become immovably lodged in the well but which subsequently can be readily removed if desired which method comprises forming said member of an aluminum alloy, positioning said member in the well and removing it when desired by dissolving said member by causing it to chemically react with a substance which will chemically react with the aluminum alloy without detrimentally affecting the ferrous metal structures in the well.

ELWIN B. HALL.

ARTHUR L. ARMENTROUT.
